UNITED STATES PATENT OFFICE

WILLIAM A. EVERE, OF MARTINSBURG, WEST VIRGINIA

RAILWAY-RAIL JOINT

Application filed June 4, 1929. Serial No. 368,284.

This invention relates to rail joints, and has for one of its objects to provide a novel device of this character which shall be adapted to hold the ends of the rails against any relative vertical or horizontal movements, and which shall be adapted to bridge the space between the ends of the heads of the rails, whereby to provide the rails with a substantially continuous tread surface and thus 10 avoid all jars incident to the passage of the wheels of a car over the joint and to prevent the wheels from bruising the ends of the heads of the rails.

To attain the foregoing and other objects, 15 the nature of which will appear as the description proceeds, the invention comprehends the provision of a rail joint embodying an inner joint plate having horizontal upper and lower edges contacting with similar surfaces on the bases and heads of the rails, a tread member carried by the joint plate and fitting in recesses formed in the ends of the rail heads, and an outer joint plate having inclined upper and lower edges contacting with similar surfaces on the rail bases 20 and heads.

The invention is hereinafter more fully described and claimed, and illustrated in the accompanying drawings, wherein:—

Figure 1 is a top plan view of a rail joint constructed in accordance with my invention;

Figure 2 is a view in side elevation of the rail joint;

Figure 3 is a sectional view taken on the vertical plane indicated by the line 3—3 of Figure 1;

Figure 4 is an elevational view of a fragmentary portion of the inner joint plate and the tread member;

Figure 5 is a perspective view of a slightly modified form of the tread member;

Figure 6 is a sectional view taken on the vertical plane indicated by the line 6—6 of Figure 5;

Figure 7 is a top plan view of a further modified form of the tread member; and

Figure 8 is a view partly in elevation and partly in vertical section of the inner joint plate and tread member shown in Figure 7.

Referring in detail to the drawings, I designates the bases, 2 the webs, and 3 the heads of a pair of railway rails. In accordance with my invention, the inner base flanges of the rails are provided at their upper sides with horizontal seats 4, the corner portions of the inner side portions of the heads are cut away 55 to provide recesses 5 and the under surfaces of these side portions of the heads are formed to provide horizontal seats 6. The depth of the recesses 5 is less than the width of the inner side portions of the heads 3 so as to permit the horizontal seats 6 to extend along the heads from points coincident with the ends of the webs 2. In all other respects the rails 60 are of well known construction.

An inner joint plate 7 and an outer joint plate 8 are secured in place by bolts 9. The inner joint plate 7 has horizontal upper and lower edges which contact with the lower rail seats 4 and the upper rail seats 6, the rail seats and the inner joint plate being similar as to length. The inner joint plate 7 is provided with a tread member 10 which is formed integrally with the upper edge thereof and which fits in the recesses 5 with its upper edge in alignment with the upper or 70 tread surfaces of the rails.

The tread member 10 is similar in contour to the recesses 5, the inclined vertical edges thereof are spaced slightly from the inclined end walls of the recesses, and the inner vertical side thereof contacts with the longitudinal walls of the recesses. The outer plate 8 has inclined upper and lower edges which contact respectively with the inclined upper sides of the outer flanges of the bases 1 and with the inclined lower outer sides of the heads 3.

Due to the contact between the horizontal edges of the inner joint plate 7 and the horizontal seats 4 and 6 of the rails, and due to the contact between the inclined edges of the outer joint plate 8 and the inclined portions of the rails, the rails are positively held against any vertical or horizontal movements, with the result that the tread surfaces of the rails are maintained in alignment. The tread member 10 of the inner joint plate 7 has its upper edge arranged in the plane of the tread surfaces of the rails and carries the wheels over the meeting ends of the heads 3.

in a manner to avoid all jars and the bruising of the ends of the heads. The formation of the contacting surfaces of the joint plates 7 and 8 and the bases 1 and heads 3 are such that when the joint plates are drawn into place through the medium of the bolts 9, the tread surfaces of the heads and member 10 will be alined.

The central portion of the inner joint plate 7 is solid throughout so as to provide a strong and rigid support for the heads 3 of the rails immediately adjacent their meeting ends.

As shown in Figures 5 and 6, the tread member, which is here designated 10^a, is removably engaged with the inner joint plate 7. A recess 11 is formed in the inner joint plate 7 for the reception of the lower portion of the tread member 10^a, and the tread member is secured to the joint plate by bolts 12. The upper and lower edges of the tread member 10^a are formed so as to permit the tread member to be reversed when the edge in use becomes worn. When both edges of the tread member 10^a becomes worn, this member may be removed and a new one substituted therefor, or if desired a new one may be substituted therefor when one of its edges becomes worn. The tread member 10 is provided with parallel rows of openings, the row of openings 13 receiving the bolts 12 when one edge of the tread member is in a position for use and the row of openings 14 receiving the bolts when the other edge of the tread member is in position for use. The recess 11 terminates short of the lower edge of the joint plate 7, and the lower edge of the tread member 10^a rests upon the bottom wall of the recess. The inner side of the upper portion of the tread member 10^a is spaced inwardly from the corresponding side of the joint plate 7 to provide the joint plate with a continuous upper edge for supporting the rail heads.

The tread member 10^b, shown in Figures 7 and 8, is removably connected to the inner joint plate 7 so as to permit it to be renewed when its upper edge becomes worn. Bolts 15 secure this tread member in place. The inner side of the upper portion of the tread member 10^b is spaced inwardly from the corresponding side of the joint plate 7, and said member is provided with a thickened lower portion 16 which provides a shoulder 17 which extends inwardly from said side of the tread member and alines with the upper edge of the joint plate 7 to provide the joint plate with a continuous upper edge for supporting the rail heads. To adapt it for the reception of the tread member 10^b, the inner joint plate 7 is provided with a recess 18, which opens out through its upper edge and inner side.

From the foregoing description, taken in connection with the accompanying drawings, it will be understood that the joint provides

for the most efficient and the strongest connection of the rail ends, that the tread members provide the rails with a substantially continuous tread surface, that in one form of the invention the tread member may be reversed or renewed, and that in another form of the invention the tread member may be renewed and provides a substantial support for the heads of the rails.

As the tread members in certain forms of the invention may be renewed, the joint may be maintained in a high state of efficiency at comparatively low cost.

While I have described the principle of the invention together with the structure which I now consider the preferred embodiment thereof, it is to be understood that the structure shown is merely illustrative and that such changes may be made, when desired, as fall within the scope of the invention as claimed.

I claim:—

1. A joint plate provided with a recess opening out through the upper edge thereof, a tread member having its lower portion arranged in the recess, the upper and lower edges of the tread member being similar, and means detachably securing the tread member to the joint plate.

2. In combination, a pair of rails provided at their inner sides with horizontal base and head seats and provided at their outer sides with inclined base and head seats, the corners of the inner side portions of the rail heads being cut away to provide registering recesses of a depth less than the width of said head portions, an inner joint plate provided with horizontal upper and lower edges contacting with the horizontal seats, a tread member carried by the joint plate and fitting in said recesses and spaced outwardly from the inner side of the joint plate to provide the joint plate with a rail head supporting element alined with the upper edge of the joint plate, and an outer joint plate having inclined upper and lower edges contacting with the inclined seats.

3. A joint plate provided with horizontal upper and lower edges, and a tread member extending upwardly from the upper edge of the joint plate at a point between the ends of the latter, the tread member being spaced outwardly from the inner side of the joint plate to provide the latter with a rail head supporting element located inwardly of said member and alined with the upper edge of the joint plate.

4. A joint plate provided with a recess extending downwardly from the upper edge thereof, the recess having a bottom wall located above the lower edge of the joint plate and an inner wall spaced outwardly from the inner side of the joint plate, a tread member having its lower portion arranged in the recess and contacting with the walls thereof,

the tread member having its upper portion arranged in upwardly extended relation to the upper edge of the joint plate and spaced outwardly from the inner side of the joint plate, and means removably securing the tread member to the joint plate.

5 In testimony whereof I hereunto affix my signature.

WILLIAM A. EVERE.
